EDWARD POWELL HOPKINS, OF NEW YORK, N. Y., ASSIGNOR TO THE PUBLISHER'S UTILITIES CO., OF NEW YORK, N. Y., A CORPORATION OF NEW YORK.

TENSION DEVICE.

1,388,342.

Specification of Letters Patent. Patented Aug. 23, 1921.

Application filed January 2, 1913, Serial No. 739,715. Renewed June 28, 1918. Serial No. 242,504.

To all whom it may concern:

Be it known that I, EDWARD POWELL HOPKINS, a subject of the King of Great Britain, residing at the city of New York, State of New York, United States of America, have invented new and useful Improvements in Tension Devices, of which the following is a full, clear, concise, and exact description, reference being had to the accompanying 10 drawing, forming a part of this specification.

This invention relates to tension devices.

The web or fabric which is operated upon by printing presses and the like is generally drawn into the machine from a roll. The 15 tension of the web tends to vary from many causes such as changes in the speed of the press or change in the diameter of the roll. It is important that an even tension be maintained on the web and that any tendency of 20 the tension to vary be immediately and positively compensated for. To this end the present invention has been devised.

One of the objects of this invention is to provide an improved means for automatically 25 maintaining a uniform tension on a web under all operating conditions.

Another object is to provide a positive and sensitive means for automatically regulating the tension on a web as it is drawn 30 into a press.

Another object is to provide an improved means which will automatically regulate the tension of a web and prevent overrunning of the web roll.

35 Other objects and advantages of the invention will hereinafter appear.

One embodiment of the invention as applied to a printing press is shown in the accompanying drawings, in which—

40 Figure 1 is a front elevation, and Fig. 2 is an end elevation.

The web roll 1 is supported on a spindle 2. The spindle 2 has its bearings in brackets 3 on the supporting frame 4. The web is 45 drawn from the roll 1, over a tension roll 5, tension controlling rolls 6 and 7 and guide roll 8 into the press.

The spindle 2 carries a friction drum 9 grooved as shown at 10 to coöperate with 50 friction brake shoes 11, V-shaped in cross-section. The friction shoes are pivoted to levers 12 and 13 which are fulcrumed respectively at 14 and 15 on a cross-link 16. Cross-link 16 is supported by an adjustable 55 screw 17 entering a socket in the frame 4.

By means of the hand-wheel 18 this screw is adjusted to provide for lateral adjustment of the web roll with respect to the press frame.

A compound lever 19 is attached at one end by link 20 to the free end of lever 13. 60 Lever 19 is also attached intermediate its ends by an adjustable link 21 to the free end of lever 12. The upper end of link 21 is provided with a hook 24 engaging a pin 25 on a short link 26 which is attached to the free 65 end of lever 12. Link 21 may be adjusted in length by means of the screw coupling 22 operated by the hand-wheel 23.

A link 27 connects the free end of compound lever 19 with a pin 28 projecting from 70 an arm 29 which is fast on one end of a rock shaft 30. Rock shaft 30 carries, at each end, a pair of arms 31 and 32 mounted fast thereon and extending in opposite radial directions therefrom. Arms 31 and 32 carry the 75 tension controlling rolls 6 and 7 respectively. Rotation of the rock shaft 30 in a counter clock-wise direction will exert a downward thrust on link 27 which will act through the levers and links described to cause the friction shoes to exert a powerful braking action 80 on the roll spindle.

A predetermined initial braking action is obtained by means of a spring 33 adjustable by a hand-wheel 34. Spring 33 exerts its 85 force through a link 36 connected to pin 28 to cause the link 27 to apply the brake. The brake may be released manually by the handle 37 on the arm 29. A latch 38 coöperating with the tooth 39 on the frame is provided 90 for holding the brake in released position. The tension roller 5 is mounted in slideable bearing blocks 40, pressed outwardly by springs 41.

In operation the spring 33 is set to exert 95 sufficient braking action on the roll spindle to maintain the required tension on the web as it is drawn into the press. The action of the spring is counteracted to a certain extent by the tension on the web which tends to rock 100 the shaft 30 in a clock-wise direction. Any tendency to increase the tension on the web will still further rock the shaft 30 clock-wise and raise up on the lever 19 to decrease the 105 braking action, while any tendency to decrease the tension on the web will act in the reverse direction to increase the braking action. A tendency to vary the web tension occurs when the press speed is changed as when the press is suddenly started or when 110

its operating speed is suddenly increased or decreased. A tendency to change the tension also results from the decrease in the size of the roll as the web is drawn off, a smaller 5 roll, of course, requiring a greater pull on the web to obtain the same linear speed as the web passes into the press. Upon breakage of the web or stoppage of the press the full strength of spring 33 will be immediately applied to set the brake to prevent 10 overrunning of the roll. The tension roll 5 compensates for slight fluctuations in tension on the web, such, for example, as may be caused by the flattened portions on a roll. 15 The tension control rollers, both acting on the brake mechanism and being positioned on opposite sides of the web causing a double deflection thereof, allow deviations in web tension to exert a multiplied effect upon the 20 brake mechanism. A more sensitive and reliable tension control mechanism is thereby produced.

What I claim as new and desire to secure by Letters Patent is:

25 1. A web tension mechanism comprising a web-roll shaft, a brake therefor, and a web control connected to said brake mechanism, said web control comprising a rock-shaft, two arms extending in different directions 30 from the shaft at each side of the path of the web, two displaceable guide rollers carried by the pairs of arms to receive the web trained under and over them respectively, a hand lever extending from the rock-shaft, 35 and a connecting rod extending downward from the lever to the brake.

2. In a web tension mechanism, the combination of a pair of frame uprights carrying supports for a web-roll shaft, a brake 40 for said shaft, a transverse rock-shaft mounted in brackets upon the press side of said uprights above the web, two arms extending in different directions from the shaft at each side of the path of the web, 45 two displaceable guide rollers carried by the pairs of arms to receive the web trained under and over them respectively, a lever extending from said rock-shaft beyond the web-roll side of the uprights, a connecting 50 rod extending downward from said lever to the brake, another rod also extending downward from the lever at the opposite side of one of the uprights from the rock-shaft, an abutment bracket projecting from said up- 55 right, and an initial tension spring inter- posed between said rod and abutment bracket.

3. A web tension equalizer for printing presses and the like, adapted to maintain a 60 substantially constant web tension in a web continuously movable, comprising a web roll shaft, a brake associated with said shaft to vary the tension in the web, a pair of web guides rotatable about a common axis and 65 upon which the web acts to produce a couple

about the common axis, and a lever system interlinking said brake and said guides to transmit the effect of varying web tension to the brake to provide corrective influences to maintain uniform web tension.

4. In a web tension mechanism, the combination of a frame having a support for a web-roll shaft, the web-roll shaft bearing a brake pulley, opposed levers carrying brake shoes, a fulcrum link connecting said levers 70 at one end, an actuating lever pivotally connected with one of the brake levers, a link connecting said actuating lever and the other of the brake levers, a connecting rod extending upward from said actuating lever, and a 75 web-controlled device connected with said rod.

5. A web tension equalizer for printing presses, adapted to maintain substantially uniform web tension in a relatively high 80 speed continuously movable web, the said equalizer comprising a shaft for supporting a web-roll, a brake mechanism associated with the shaft, the said brake mechanism including friction members, and a resilient 85 means normally acting to apply the friction members to the shaft, a pair of web guides bodily rotatable about a common axis and adapted to guide the web in a doubly deflected path to produce a couple about the 90 common axis, means for transmitting the movement of the pair of web guides to the brake mechanism whereby the said movement tends to neutralize the effect of the resilient member so that the effect of the bodily 95 rotatable web guides is to produce a multiplied effect of the web tension to act in opposition to the tension member whereby substantially uniform web tension is maintained.

6. A web tension equalizer for printing 10 presses wherein a continuously movable web is withdrawn from a web roll, the said equalizer comprising a web roll shaft, a brake mechanism associated with the shaft including friction members, a resilient member, and means connecting the friction members and the resilient member whereby the said friction members normally act to restrain the shaft against rotation, a pair of 11 guide rollers, an arm connecting the guide rollers and having a pivotal support therebetween, the said guide rollers being bodily 11 rotatable about the pivotal support, means connecting the arm and the brake mechanism, the said guide rollers functioning to 12 guide a web in a doubly deflected path, so that the web tension acting upon the bodily rotatable rollers forms a couple about the point of pivotal support, the effect of which is transmitted to the braking mechanism to 13 act in opposition to the resilient member so that a sensitive braking action is effected to maintain substantially uniform web tension.

7. In a printing press wherein a continuously 14 movable web is withdrawn from a

web roll, a web tension equalizer comprising a web roll shaft, a brake mechanism associated with the shaft and including friction members, a resilient member, means connecting the friction members and the resilient member whereby the said friction members normally tend to restrain the shaft against rotation, and means for adjusting the resilient member to vary the effective brake tension, a pair of web guide rollers, an arm connecting the guide rollers and having a pivotal support therebetween, the said guide rollers being bodily rotatable about the pivotal support, means connecting the arm and brake mechanism, the said guide rollers functioning to guide a web in a doubly deflected path so that the web tension acting upon the bodily rotatable rollers forms a couple about the point of pivotal support the effect of which is to multiply the web tension so that the effect of the couple may be transmitted to the braking mechanism to act in opposition to the resilient member so that sensitive braking action is obtained to maintain substantially uniform web tension, the said adjusting means functioning independent of the weight of the web guides and the arms connecting the same, and to compensate automatically for worn friction members.

8. A web tension mechanism comprising a web roll shaft, a brake therefor, a web control for the brake having a rock shaft, a plurality of arms extending in different directions from the shaft at each side of the path of the web, and guide rollers carried by the arms and arranged to receive the web under and over them respectively, a tension roll over which the web is received as it passes from the web roll to the guide rollers, means for maintaining the tension roll in yielding contact with the web, adjustable yielding means coöperating with the brake and maintaining a predetermined initial tension in the web, and means connecting the arms and the brake for transmitting movement from the rollers to the brake.

9. A web tension equalizer for maintaining a substantially constant tension in a continuously moving web, comprising a web roll shaft, a brake therefor for varying the tension in the web, a pair of web guides rotatable about a common axis and upon which the web acts to produce a couple about a given axis, a tension roll arranged in the path of the web, means for maintaining the tension roll in yielding contact with the web, adjustable yielding means coöperating with the brake and maintaining a predetermined initial tension in the web, and a lever system interlinking the brake and the guides to transmit the effect of varying web tension to the brake to provide corrective influences to maintain substantially uniform web tension.

In witness whereof, I have hereunto subscribed my name in the presence of two witnesses:
